COMBINED BATTERY PACK AND CHARGER UNIT

George R. Hartz, Canoga Park, Calif., assignor to
Berkey/Colortran Mfg., Inc., Burbank, Calif.

Filed Oct. 12, 1970, Ser. No. 25,453

Term of patent 14 years

Int. Cl. D13—02

U.S. Cl. D26—15

FIG. 1.

FIG. 2.

FIG. 3.

FIG. 1 is a front exploded perspective view of a combined battery pack and charger unit showing my new design;

FIG. 2 is a rear exploded perspective thereof; and

FIG. 3 is a perspective view in a fully assembled position.

I claim:

The ornamental design for a combined battery pack and charger unit, substantially as shown.
